(57) **CLAIM**

The ornamental design for a charger, as shown and described.

DESCRIPTION

FIG. 1 is a front elevational view of a charger showing our new design.

FIG. 2 is a back elevational view;

FIG. 3 is a left side view.

FIG. 4 is a right side view.

FIG. 5 is a top plan view.

FIG. 6 is a bottom plan view; and,

FIG. 7 is a perspective view.

The broken lines shown represent unclaimed subject matter and form no part of the claim. Where broken lines abut a claimed surface it is understood that those lines represent an unclaimed boundary between claimed and unclaimed surfaces. None of the broken lines form any part of the claimed design.
